ATTORNEY

UNITED STATES PATENT OFFICE.

ARTHUR LOMBERG, OF ELIZABETH, NEW JERSEY, ASSIGNOR TO LEW JOSEPH, OF EAST ORANGE, NEW JERSEY.

NAIL-BUFFER.

1,053,839.

Specification of Letters Patent.

Patented Feb. 18, 1913.

Application filed January 20, 1912. Serial No. 672,505.

To all whom it may concern:

Be it known that I, ARTHUR LOMBERG, a citizen of the United States, residing at Elizabeth, in the county of Union, State of New Jersey, have invented certain new and useful Improvements in Nail-Buffers, of which the following is a specification.

This invention relates generally to manu-
10 nail buffers or polishers, and has for one of
its objects to provide means whereby a pol-
ishing material may be readily removed,
and also kept stretched taut while the buffer
is held by the handle.

15 Another object is to provide an adjustable
handle which may be adjusted so as to be
out of the way when the article is to be
packed.

Further objects will appear from the de-
20 tailed description, and will be particularly
pointed out in the claims.

In the accompanying drawing which illus-
25 trates this invention, Figure 1 is an eleva-
tion of my improved buffer; Fig. 2 is an
elevation partly in section showing the han-
dle adjusted in a position it is to assume
when the article is to be packed; Fig. 3 is
30 a plan view of the structure illustrated in
Fig. 1; Fig. 4 illustrates the body portion
of the buffer, with the polishing material or
chamois and also the handle removed; Fig.
35 5 is a view partly in section illustrating the
chamois; Figs. 6 and 7 are respectively an
elevation and plan of the tightening band.

40 The numeral 1 indicates the top of the
body of the buffer, which may be of any
suitable material such as wood, bone, celluloid,
etc., and 2 indicates a covering which
secures padding 3 to the top 1, and is held
45 in place by cord 4 or any other suitable
means.

50 5 indicates the polishing material which is
generally of chamois skin, and is held in
place by a band 6, made of metal or any
other suitable material. This band has at
each extremity an aperture 7.

Pivotal mounted in the apertures 7 of
55 band 6, is a handle 8, formed preferably of
spring sheet metal, and having pins 9 ex-
tending through the apertures 7 and per-
forations 10 in the polishing chamois and into
small cavities in the body 1. Owing to this
pivotal mounting, the handle 8 may assume
any position to suit the hand of the operator,

and may also be turned out of the way into 55
the position indicated in Fig. 2, when the
buffer is to be packed. When the handle 8
is grasped by the operator it is flexed so as
to exert an upward pull on the band 6,
which is thus raised slightly and accordingly 60
serves to tighten the polishing chamois 5.
When it is desired to renew the chamois, the
handle 8 is removed by snapping pins 9 out
from the apertures 7, the band 8 is slipped 65
off and chamois 5 removed. The inverse 65
operations are gone through when the new
chamois is replaced.

Various modifications may be made with-
out departing from the spirit and scope of
this invention as defined in the accompany- 70
ing claims.

I claim:

1. In a nail buffer, a body portion, and a
handle pivoted thereto at points adjacent
the top of the end portions of said body por- 75
tion, said handle consisting of a curved
piece adapted to swing over from a position
above the body portion to a position below
the body portion and fitting snugly there-
with. 80

2. A nail buffer comprising a body por-
tion, and a handle consisting of a bowed
piece having pins extending inwardly from
its extremities, and projecting into the body
portion at points adjacent the top portions 85
of the ends thereof, said handle being adapt-
ed to swing from a position above the body
portion to a position below said body por-
tion and to lie snugly thereagainst.

3. A nail buffer comprising a body por- 90
tion, a polishing chamois and a band adapt-
ed to embrace said polishing member and
hold the same in position on the body por-
tion, said band having apertures at its oppo-
site extremities, and a handle having pins 95
adapted to pass through the apertures in
said band, and to pivotally swing about said
body portion.

4. A nail buffer comprising a body por-
tion, a polishing member and a band adapt- 100
ed to embrace said polishing member and to
hold the same in position on the body por-
tion, said band having apertures at its oppo-
site extremities, and a handle consisting of
a bowed strip having inwardly extending 105
pins at its opposite extremities, said pins ex-
tending through the apertures in the band,
the handle being adapted to swing from a

spaced position above the body portion to a position below said body portion, and lying snugly thereagainst.

5. A nail buffer comprising a body portion, a polishing member and a handle, a band embracing said polishing member and adapted to hold the same in position on the body portion, said handle consisting of a flat bowed spring member having inwardly 10 projecting pins at its extremities, and adapted to pass through apertures in the band and polishing member and into the body portion, said handle being adapted when flexed by the hand of the operator to tighten

the polishing member about the body portion. 15

6. A nail buffer comprising a body portion, and a bail shaped handle removably pivoted thereon at a point adjacent the top of the end portions thereof, said handle being adapted to swing from a position above the body portion where it is spaced therefrom, to a position below thereto, and lying snugly thereagainst. 20

ARTHUR LOMBERG.
